BY *Minn Co.*

ATTORNEYS

UNITED STATES PATENT OFFICE.

ROBERT JAMES ESTES, OF COALGATE, OKLAHOMA.

PEN.

Application filed August 22, 1922. Serial No. 583,549.

To all whom it may concern:

Be it known that I, ROBERT J. ESTES, a citizen of the United States of America, and a resident of Coalgate, in the county of Coal 5 and State of Oklahoma, have invented a new and Improved Pen, of which the following is a description.

My invention relates to writing pens and particularly to a writing pen employing a 10 stylus.

The general object of my invention is to provide a pen of the indicated type improved in various particulars with respect to the feed means and the regulating means 15 thereof.

The nature of my invention and its distinguishing features and characteristics will appear clearly as the description proceeds.

Reference is to be had to the accompanying drawings forming a part of this specification, it being understood that the drawings are merely illustrative of one example of the invention.

Figure 1 is a side elevation of a pen embodying my invention;

Figure 2 is a vertical section, part of the staff being in elevation;

Figures 3 and 4 are cross sections respectively on the lines 3-3 and 4-4 of Figure 2.

In carrying out my invention in accordance with the illustrated example, a staff 10 is formed at the front end with an axial blind bore or recess 11 of square or other non-circular form. The axle of the recess 30 11 receives a shank 12 of a stylus 13, said

shank having a square or other non-circular cross section to conform to said recess to prevent the stylus from turning about its own axis in the staff 10.

The stylus 13 at an intermediate portion thereon is formed with external threads 14 engaging internal threads in the bore of a partition 15 in the cap 16 of the pen, said cap being socketed at its rear end to receive 45 the forward end of the staff 10.

The front end of the stylus 13 is tapered and formed with a twist or helical convolutions, the grooves of the helical convolutions increasing in size rearwardly from the writing point. The tapered end 17 of the stylus 50 is adapted to be protruded beyond the front of the cap 16 for writing and in order to regulate the feed of the ink the cap 16 is provided with a rubber disk 18 having a central hole for the passage of the stylus point. The disk 18 is clamped in place be-

tween the front flange 19 on the cap 16 and a washer 20 in the cap 16 at the back of said disk 18.

The disk 18 functions in regulating the flow of the ink along the helical grooves presented by the tapered end 17 of the stylus. The stylus may be projected more or less beyond the end of the cap 16 by turning the staff 10 since with the turning of said staff the recess 11 and square shank 12 cause the stylus 13 to be turned also, so that the engagement of the threads 14 of the stylus with the threads of the partition 15 causes the stylus to be advanced or retracted and thereby, owing to the tapered end 17 a greater or less space for ink flow will be afforded between the exterior of said tapered portion and the rubber disk 18.

As an aid to hold a supply of ink I provide a wire mesh sleeve 21 within the cap 16 in front of the partition 15 and terminating adjacent to the washer 20 that clamps the rubber feed disk 18, said cap 16 having ample openings 22 at the sides thereof to afford entrance of ink to said mesh sleeve 21.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A writing pen including a stylus having a tapered front end, an element with which said stylus has threaded engagement, feed control means through which the tapered portion of the stylus may be projected, a turnable pen staff, and means to turn the stylus by the turning of said staff.

2. A pen including a stylus having a tapered front end presenting spiral convolutions, said stylus being adjustable longitudinally, and means adjacent the said tapered portion through which said tapered portion may be variously projected by the longitudinal movement of the stylus.

3. A pen including a staff, a cap thereon, a stylus disposed axially in said cap and formed with a front end tapering and presenting helical grooves, said staff being turnable relatively to the cap and said stylus at its rear end having engagement with the staff to move longitudinally therein but to

- be turned by the turning of the staff, and feed control means on the cap at the front end through which the tapered portion of the stylus may be variously projected.
- 5 4. A pen including a staff, a cap thereon, a stylus disposed axially in said cap, and tapered at its front end, said staff being turnable relatively to the cap and said stylus at its rear end having engagement with
- 10 the staff to move longitudinally therein but to be turned by the turning of the staff, and feed control means on the cap at the front end through which the tapered portion of the stylus may be variously projected.
- 15 5. A writing pen including a stylus having a tapered front portion, and a rubber disk transverse to said tapered portion and through which said tapered portion may be variously projected.
- 20 6. A writing pen including a stylus having a tapered front portion presenting helical grooves, and a rubber disk transverse to said tapered portion and through which said tapered portion may be variously projected.
7. A writing pen including a staff, a cap 25 on the said staff presenting side openings, a sleeve of wire mesh within the cap at said openings, feed control means at the front end of the cap, and a stylus disposed axially in the cap and adjustable therein to variously project the stylus through said feed control means.
8. A pen including a staff, a cap thereon presenting side openings, a sleeve of wire mesh within the cap at said openings, a rubber disk on the cap at the front end, a stylus 35 having a tapered front end presenting a helical groove, and means to adjust the stylus longitudinally to variously project its said tapered portion through said disk. 40

ROBERT JAMES ESTES.
